DESIGN FOR A RANGE FINDER BRACKET

Leon Hartman, New York, N. Y., assignor to Ab-
bey Photo Corporation, New York, N. Y., a cor-
poration of New York

Application May 28, 1938, Serial No. 77,457

Term of patent 7 years

To all whom it may concern:

Be it known that I, Leon Hartman, a citizen of the United States and resident of the Borough of Manhattan, in the city and State of New York, have invented a new, original, and ornamental Design for a Range Finder Bracket, of which the following is a specification, reference being had to the accompanying drawing, forming a part thereof.

Fig. 1 is a perspective view of the bracket from the side bearing the range finder eye-piece.

Fig. 2 represents a top plan view of the bracket.

Fig. 3 represents an elevation of the bracket looking in the direction of the range finder eye-piece, and

Fig. 4 represents an elevation of the bracket taken at right angles to the view shown in Fig. 3.

What I claim is:

The ornamental design for a range finder bracket, substantially as shown and described.

LEON HARTMAN.
